Primary Examiner — Cynthia M. Chin(74) Attorney, Agent, or Firm — Perry Hoffman(57) CLAIM

The ornamental design for a projectile magazine sidewall, as shown and described.

DESCRIPTION

FIG. 1 is a perspective view of the projectile magazine sidewall of the instant invention;

FIG. 2 is a right side elevational view thereof;

FIG. 3 is a left side elevational view thereof;

FIG. 4 is a front view thereof;

FIG. 5 is a rear view thereof;

FIG. 6 is a top view thereof;

FIG. 7 is a bottom view thereof; and,

FIG. 8 is a perspective view of the projectile magazine sidewall of the instant invention shown in an assembly environment with broken surface lines for illustrative purposes forming a sidewall portion thereof.

The broken lines are for the purpose of illustrating portions of the article that form no part of the claim.
